(57) **CLAIM**

The ornamental design for a plug-in device, as shown and described.

DESCRIPTION

FIG. 1 is a front elevational view of a plug-in device showing my new design;

FIG. 2 is a rear elevational view thereof;

FIG. 3 is an elevational view of the right side thereof;

FIG. 4 is an elevational view of the left side thereof; and,

FIG. 5 is a perspective view thereof.

The broken line portion of the figure drawings is included to show unclaimed subject matter only and forms no part of the claimed design.
